Matthew W. Mitchell(57) CLAIM

The ornamental design for a shirt as shown and described.

DESCRIPTION

FIG. 1 is a front perspective view showing my new design; FIG. 2 is a front view thereof; FIG. 3 is a left-side view thereof; FIG. 4 is a right-side view thereof; and, FIG. 5 is a top plan view thereof.

Cross-hatch marks are used only to indicate fabric and contour and are not part of the claimed design. The dot-dashed lines on the neck, torso area, and arm sleeve illustrate a boundary of the claim and form no part of the claimed design.
